UNITED STATES PATENT OFFICE

2,303,150

COOLING UNIT FOR REFRIGERATORS

Edwin J. Van Riper, Schenectady, N. Y., assignor
to General Electric Company, a corporation of
New York

Application December 17, 1941, Serial No. 423,357

2 Claims. (Cl. 62—126)

My invention relates to cooling units for refrigerators and particularly to cooling units including removable cooling containers.

It is an object of my invention to provide a cooling unit for refrigerators having a removable cooling container and an improved arrangement for cooling the container while it is in position in the cooling unit.

Further objects and advantages of my invention will become apparent as the following description proceeds, and the features of novelty which characterize my invention will be pointed out with particularity in the claims annexed to and forming a part of this specification.

For a better understanding of my invention reference may be had to the accompanying drawing in which Fig. 1 is a front elevation view of the upper portion of a household refrigerator provided with a cooling unit embodying my invention; Fig. 2 is an enlarged side elevation view, partly in section, of the upper portion of the cooling unit shown in Fig. 1; and Fig. 3 is a sectional front elevation view of the cooling unit shown in Fig. 1.

Briefly, the cooling unit shown in the drawing comprises a sheet metal evaporator constituting a housing and having freezing shelves for the freezing of water, desserts, and the like extending across the interior of the housing. In the upper portion of the housing is arranged a container having an open front and which is closed by a door on the housing. The container is spaced from the walls of the housing and may be removed by sliding it out of the wall opening of the housing. In order to cool the container to temperatures above freezing but suitable for the preservation of meats and the like, a refrigerated plate or shoe is resiliently mounted on one of the upper walls of the housing, and when the container is in place this plate is pressed against the wall of the container and cools the container. The refrigerant connections to the cooling plate are flexible or resilient and the container may be moved in or out of the housing in sliding engagement with the plate without disturbing the refrigerant connections.

Referring now to the drawing, in Fig. 1 I have shown a household refrigerator comprising a thermally insulated cabinet 10 having a door 11 and provided with a cooling compartment 12. In order to cool the compartment I provide a cooling unit or evaporator 13 in the form of a sheet metal housing having a door 14 closing the upper portion thereof. The evaporator 13 is provided with a refrigerant header 15 and re-

frigerant passages 16 in the walls of the housing. Shelves 17 and 18 extending laterally between the inner walls of the housing are provided to support freezing trays and the like, and the bottom wall 19 of the evaporator also serves as a freezing tray support.

The details of construction of the cooling unit are more clearly shown in Figs. 2 and 3. The walls of the housing 13 comprise inner and outer sheet metal portions 20 and 21, respectively, the lower shelf 17 being formed by bending the sheet metal structure back upon itself. The upper portion of the right-hand side wall of the housing comprises a single sheet metal wall 22, and the upper shelf 18 comprises top and bottom sheet metal portions 23 and 24, respectively, the shelf 18 being welded or otherwise suitably secured between the walls of the housing on a flange 25 comprising a portion of the lower sheet 24 and an angle piece 26 comprising a separate strip of metal secured to the left-hand wall of the housing. The header and the several refrigerant passages in the evaporator walls and in the shelves are formed by providing suitable corrugations or indentations in one or both of the sheet metal portions of the wall and thereafter welding the sheets together around their peripheries and between the indentations to form a leakproof rigid evaporator structure.

Some foods, such as meats, are best kept at temperatures above freezing, and yet considerably below the temperature prevailing in the main food compartment of the refrigerator. In order to provide a zone in which meats may be preserved within the desired temperature range, I provide a container 27 in the upper portion of the evaporator above the shelf 18. The container 27 is open at its front end which lies adjacent the front end of the evaporator and is closed by the door 14. The container 27 is spaced from the walls of the housing including a top wall indicated at 28 and which comprises the top inner wall of the compartment 12. The spacing of the container 27 above the shelf 18 is sufficiently great to provide room for the placing of freezing trays on the shelf below the container. The container is maintained in position within the housing on suitable guides or rails 29 and 30, the container being provided with a plurality of feet 31 for engaging the guides. In order that the temperatures within the container 27 shall not become too low, it is desirable that the container should not be in direct heat exchange relation with any substantial quantity of liquid refrigerant, and it is for this

reason that the container is spaced from the header and other liquid containing portions of the evaporator. However, it is desirable to provide some direct cooling of the container, and for this purpose I provide a cooling element or plate 32 adjacent the upper portion of the container. The element 32 is pressed resiliently against the container by a suitable spring 33 which is secured to the wall 22 of the evaporator on suitable pins 34 that fit slots 35 at the ends of the spring. The cooling plate may be removed from the wall 32 by flexing the ends of the spring out of their positions on the pins 34. The plate 32 comprises a sheet metal body portion 36 and a U-shaped refrigerant conduit 37 extending around the edges of the plate 36, the edge portions of the plate being bent around the conduit as indicated at 38.

It is apparent that the container 27 may be moved in and out of the housing or evaporator 13 in sliding engagement with the plate 32. When the container is in the housing, the cooling effect of the plate 32 in the upper portion of the container 27 cools the container and induces some circulation of air therein. The conduit 37 is provided with inlet and outlet connections 39 and 40, respectively, for admitting refrigerant to and withdrawing refrigerant from the conduit. The connections 39 and 40 are made sufficiently resilient or flexible to allow the necessary movement of the plate 32 without disturbance the refrigerant connections thereto. The arrangement of the refrigerant connections for admitting refrigerant to the passages in the walls of the housing 13 and for withdrawing vaporized refrigerant therefrom have not been shown as they form no part of the present invention.

During the operation of the refrigerator the container 27 may be taken out of the housing for cleaning or in order to provide greater space above the shelf 18 when the container itself is not required to be used, and it is unnecessary to interfere with any of the refrigerant connections to the container.

From the foregoing, it is readily apparent that I have provided a simple and easily constructed arrangement for securing a zone suitable for the preservation of meats and similar foods and which includes a cooling container, or compartment, cooled by direct heat transfer with a suitable plate or cooling element and which may be removed from the refrigerant evaporator without disturbing any refrigerant connections.

While I have shown and described my invention in connection with a particular form of cooling unit for household refrigerators, other applications will readily be apparent to those skilled in the art. I do not, therefore, desire my invention to be limited to the particular construction shown and described, and I intend in the appended claims to cover all modifications within the spirit and scope of my invention.

What I claim as new and desire to secure by Letters Patent of the United States is:

1. A cooling unit for a refrigerator comprising a housing, means providing a conduit for containing refrigerant to cool the walls of said housing, a metallic container slidably mounted within said housing and spaced from the walls thereof, said container being removable from said housing, a movable cooling element arranged between said container and the walls of said housing and having a refrigerant passage therein and refrigerant inlet and outlet connections, and resilient means for pressing said cooling element into contact with said container to cool said container, said container and said cooling element being so constructed and arranged that said container may be moved in and out of said housing in sliding engagement with said element and without disturbing the refrigerant connections to said cooling element.

2. A cooling unit for a refrigerator comprising a housing having an opening in one side thereof, a metallic container arranged within said housing and spaced from the walls thereof, guides secured on the walls of said housing for slidably receiving said container and for maintaining said container spaced from the walls of said housing, and means including a plate and a mounting therefor for securing said plate in said housing in heat exchange relation with said container, said mounting including a spring secured to a wall of said housing for pressing said plate resiliently against said container, said plate comprising a sheet metal member having a flat surface of substantial area adapted to engage said container and a refrigerant conduit secured in good heat exchange relationship with said sheet metal member, refrigerant inlet and outlet connections for said conduit, said container and said plate being so constructed and arranged that said container may be moved into and out of said housing on said guides without disturbing the refrigerant connections of said conduit.

EDWIN J. VAN RIVER.
